[57] **CLAIM**

The ornamental design for a frame for mounting electronic equipment, as shown and described.

DESCRIPTION

FIG. 1 is an elevational view of the lefthand side, which is symmetrical with respect to the righthand side;

FIG. 2 is a front elevational view thereof;

FIG. 3 is a rear elevational view;

FIG. 4 is a top plan view;

FIG. 5 is a bottom plan view; and,

FIG. 6 is, on an enlarged scale, a partial perspective view showing a few details on the outside of the frame elements which can not be drawn on the scale of the previous figures and showing also those sides of the elements which are directed towards the interior of the frame.

The view of FIG. 6 is shown fragmented for clarity of illustration.

The features of the undisclosed inside view of the bottom structure of FIG. 6 are understood to be identical in appearance to the fragmented portion shown.

The undisclosed inside view of the top structure is identical in appearance to the view shown in FIG. 6.
